UNITED STATES PATENT OFFICE.

ALBIN OLSSON, OF RENTON, WASHINGTON.

LOG-CAR.

1,074,812.

Specification of Letters Patent.

Patented Oct. 7, 1913.

Application filed May 24, 1913. Serial No. 769,737.

To all whom it may concern:

Be it known that I, ALBIN OLSSON, a citizen of the United States, residing at Renton, in the county of King and State of Washington, have invented a new and useful Log-Car, of which the following is a specification.

This invention relates to improvements in log cars and more particularly to a log car of the class known as telescoping cars.

An object of the present invention is to provide a longitudinally extensible and contractible car with means secured thereto whereby an air brake of the ordinary type may be installed upon the car.

A further object of the invention is to provide a longitudinally extensible and contractible car with an air brake of the ordinary type secured thereto and adjustable means whereby the air brake is adapted to operably engage the trucks regardless of the distance apart of the same.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the drawings accompanying this specification and forming a part thereof, the preferable form of my invention is illustrated, in which:—

Figure 1 is a side view in elevation of my improved car. Fig. 2 is a bottom plan view thereof with the trucks removed. Fig. 3 is a detail view of the main beam or center sill of the car. Fig. 4 is a detail view in cross section showing the interlocking main beams.

Referring to the drawings in which similar reference numerals designate corresponding parts throughout the several views, 1 are the car trucks which are provided with the usual brake rigging generally designated by the numeral 2. Pivotal secured to the trucks by the king bolts 3 are the car bolsters 4 which in the present instance are adapted to support the logs which the car in question is adapted to transport.

In order that the car trucks and bolsters 55 supported thereby may be positioned at varying distances apart in order to accommodate logs of different lengths, the telescoping or interlocking main beams 5 and 6 are provided, a cross sectional view of which 60 is illustrated in Fig. 3 of the drawings. The main beams may be interlocked as shown in Fig. 4, in which the upper beam 6' is provided with downwardly extending tongues 65 interlocking with upstanding tongues of the beam 5'. The main beams or center sills 5 and 6 are rigidly secured to the bolsters 4 and are adapted to hold the same in spaced relation, it being noted that the said beams extend beyond the bolsters and are provided 70 at their outer extremities with suitable car coupling members 7. The main beams 5 and 6 are preferably formed of metal and are provided with a number of slots or apertures 8 extending therethrough and which 75 apertures are adapted to receive suitable holding bolts or pins 9 therein, there being suitable cotter pins 10 or other equivalent means secured to the outer extremities of the bolts to prevent the accidental displacement 80 thereof.

In order that both of the trucks may be provided with automatic brakes operated from a common brake cylinder, mechanism as illustrated in Fig. 2 is employed and this 85 mechanism comprises an air brake cylinder 11 which is operably connected to the floating lever 12 to one extremity of which is secured the reach rod 13 which extends to the forward truck and is adapted to operatively engage the brake rigging positioned 90 thereon. A suitable hand brake operating mechanism 14 is pivotally secured to the remote end of said floating lever.

Pivotal secured to the end of the center 95 beam 6 which supports the cylinder 11 is a transverse lever 15 the one extremity of which is forked as at 16 and is adapted to engage one of a plurality of apertures 17 in the reach rod 18 which extends to the 100 rear truck and is operatively connected to the brake rigging thereon. The manner in which the reach rods 13 and 18 engage and are operatively connected to the truck brake rigging is of the usual and ordinary type and 105 includes the fulcrumed levers 19 as illustrated in Fig. 2. An operating link 20 connects the floating lever 12 with the fulcrumed lever

15 so that the forward and rear truck brakes will be applied simultaneously and operated by the common air brake cylinder 11.

From the foregoing it will be apparent 5 that as the two trucks are extended or retracted the pin 21 which extends through the forked portion of the fulcrumed lever 15 and engages one of the apertures 17 is withdrawn, which allows the reach rod 18 10 to take up a new position with respect to the lever 15 after which the pin 21 is reinserted in place and the brakes of the two trucks will then be operatively connected to the brake operating mechanism.

15 Rigidly secured to the center beam 5 is the air pipe 22, the same being provided with a number of flexible hose couplings 23 positioned at various intervals therealong and which flexible hose couplings are adapted 20 to engage a single hose coupling 24 which is secured to the air pipe 25 positioned upon and secured to the main beam 6. Each of the hose couplings 23 are provided with suitable shut-off valves 26 so that when a 25 particular hose coupling is not in use, it may be closed to prevent the escapement of air therefrom. The flexible hose couplings are of the type such as are used at the extremities of the car as shown at 27.

30 From the foregoing it will be apparent that I have provided a car which is longitudinally extensible and contractible and at the same time have provided an air brake operating mechanism secured thereto and 35 which mechanism is adapted to operate the brakes of the forward and rear trucks regardless the distance the same are located apart. The bolsters of the cars are used to directly support the logs or other material 40 of considerable length and limited cross section and due to the construction above outlined, the car will be comparatively light in weight which is of importance in the mountainous logging districts where the 45 empty cars are drawn back to receive a new consignment of logs thereon. Furthermore the conditions met in this service require that substantial brakes be provided which renders it almost absolutely necessary that 50 air brakes be used. By the arrangement of parts as I have outlined, the single and ordinary air brake unit may be secured to each of the cars and is adapted to adjustably and operatively engage the brake rigging provided upon each of the trucks. Furthermore the providing of a number of 55 hose couplings at various intervals along the divided air pipe which extends along the car allows the said pipe to also take up the 60 differences in length between the two trucks.

The service for which the cars are to be used makes it necessary that the distance between the two trucks of each and every car may be adjusted and in the construction 65 hereinbefore described this is readily taken

care of by means of the beams rigidly secured to each truck and which are adapted to telescope one within the other and the pins 9 adapted to hold the telescope beams in rigid relation.

Having thus fully described my invention what I claim is:—

1. A log car comprising trucks with brake rigging thereon, telescoping main beams secured to the said trucks, and air brake mechanism rigidly secured to one of the said beams and adapted to adjustably and operatively engage the said truck brake rigging.

2. A longitudinally extensible and contractible log car comprising trucks with brake rigging thereon and bolsters pivotally secured thereto, main beams rigidly secured to said bolsters and insertible one within the other, said beams provided with transverse apertures extending therethrough adapted to align and receive holding means therein, said holding means adapted to hold said beams in fixed relation, and an air brake operating mechanism rigidly secured to one of the said main beams and operatively and adjustably engaging the truck brake rigging.

3. A log car comprising trucks with brake rigging secured thereto, bolsters pivotally secured to the said trucks, a main beam rigidly secured to one of the said bolsters and provided with a plurality of apertures extending transversely therethrough, a hollow main beam rigidly secured to the other of said bolsters and provided with a plurality of apertures extending transversely therethrough and aligning with the apertures in the first mentioned main beam, said main beams insertible one within the other, means insertible into the aligned beam apertures adapted to hold the same in fixed relation, an air brake operating mechanism secured to the said hollow beam and adapted to engage the truck brake rigging there adjacent, and a reach rod operatively connected to the 110 said hollow beam and adapted to engage the truck brake rigging of the other truck and provided with a plurality of apertures extending therethrough, said reach rod adjustably engaging the said air brake operating mechanism, air pipes rigidly secured to the said telescoping beams, one of the said air pipes provided with a plurality of hose couplings arranged at intervals therealong, the other of said air pipes provided with a hose coupling adapted to engage the hose couplings 120 of the other air pipe.

4. In a longitudinally extensible and contractible log car, the combination of trucks with brake rigging thereon, bolsters pivotally secured thereto, metallic main beams rigidly secured to said bolsters and insertible one within the other, an air brake cylinder rigidly secured to one of the main beams and operatively engaging the brake rigging of the adjacent truck, adjustable means en- 130

gaging the brake rigging of the other truck and adjustably engaging the said other truck operating mechanism, air pipes rigidly secured to the said main beams, one of said air pipes provided with hose couplings arranged at intervals therealong, a single hose coupling secured to the other of said air pipes and adapted to engage one of the said plurality of hose couplings of the other of the air pipes, and means for holding the said beams in fixed adjusted relation.

In testimony that I claim the foregoing as my own, I have hereto affixed my signature in the presence of two witnesses.

ALBIN OLSSON.
